CAN CONVEYING AND FILLING MACHINE

William C. Gridley and Edward T. Magnus, Oakland, Calif., assignors, by direct and mesne assignments, of one-half to said Gridley and one-half to F. M. Ball & Company, Oakland, Calif., a corporation of Nevada

Application June 28, 1939, Serial No. 281,584

7 Claims. (Cl. 226—95)

The invention relates to canning machinery and more particularly to machines for feeding a plurality or train of cans to and past a filling station or trough for filling of the cans with fruit or vegetables or the like to be canned.

An object of the present invention is to provide a can feeding and filling machine which will be compact in construction and arranged with all of the working parts thereof below the plane of an elongated filling trough or table, and within the horizontal confines of the table whereby a battery of persons may be positioned along the table without interference from the operating machinery, and wherein the machine is operative to cause the movement of a continuous line or train of cans along the table with the open tops of the cans positioned most effectively for filling.

Another object of the invention is to provide a machine of the character described in which the cans are fed through the filling table in a position wherein the open tops of the cans will register with an opening in the filling table and thereby during the filling operation, form in effect a part of the filling table.

A further object of the invention is to provide a can feeding and filling machine of the character above which is particularly adapted for the filling of halved peaches into the cans and wherein the can conveying mechanism is so arranged as to discharge the cans from the mechanism for filling without danger of cutting or bruising portions of the fruit extending above the open tops of the cans.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a plan view of a can conveying and filling machine with portions of the machine broken away to show underlying parts.

Figure 2 is a side elevation of the machine illustrated in Figure 1.

Figure 3 is a cross-sectional view taken substantially on the plane of line 3—3 of Figure 1.

Figure 4 is an enlarged cross-sectional view of one side portion of the machine illustrated in Figure 3.

Figure 5 is a plan view of a plate carried by one of the can conveyors.

Figure 6 is a cross-sectional view of the plate taken substantially on the plane of line 6—6 of Figure 5.

Figure 7 is an enlarged fragmentary vertical cross-sectional view taken substantially on the plane of line 7—7 of Figure 1.

Figure 8 is an enlarged fragmentary vertical sectional view taken at an opposite end of the machine, as indicated by the plane of line 8—8 of Figure 1.

The can feeding and filling machine of the present invention consists briefly of an elongated trough and filling table adapted to receive fruit, vegetables or other material to be canned, and a can conveying mechanism which is operatively associated with the table for continuously moving a line or train of cans along the opposite longitudinal edges of the table and with the open can tops in registration with openings in the filling table for ready movement of the material from the table into the cans. In accordance with the present construction, the can feeding and conveying mechanism is completely disposed under the filling table and within the horizontal confines thereof, so as to enable the positioning of a row of operators along each side of the table for filling of the cans.

With reference more specifically to the accompanying drawings, the machine of the present invention consists of a material trough or table 11 of elongated form, which is supported in generally horizontal position by a supporting frame made up of a plurality of vertical and horizontal supporting members 12. As will be best seen from Figures 1 and 3, the table is formed with a pair of horizontally spaced longitudinally extending portions 13 and 14 concave in cross-section, as seen in Figure 3, and which are supported at their inner longitudinal edges 16 and 17 on longitudinal angle bars 18 and 19. The opposite longitudinal sides 21 and 22 of the members 13 and 14 are supported on longitudinal angle bars 23 and 24 and as will be seen in Figure 4, overhang such bars. Spaced outwardly from the longitudinal sides 21 and 22 are longitudinal side members 26 and 27 which are supported at their inner longitudinal ends 28 and 29 upon channels 31 and 32 supported on upright frame members 12a, 12b. The side members 26 and 27 are preferably beveled upwardly and outwardly so as to define longitudinal side barriers for the table.

A food or material conveyor 33, here in the form of a horizontal endless belt, is positioned centrally and longitudinally of the table and is supported with the upper flight 34 thereof upon the angle bars 18 and 19 in overlying position to

the inner longitudinal edges 16 and 17 of the table members. The belt is here carried upon rollers 39 and 41 at the opposite ends of the machine. A deflector 38 mounted over the top flight of the belt and having a plurality of laterally extending members 37 serves to direct the material from the belt into the opposite side members 13 and 14 of the table. Any suitable means may be employed for feeding of material onto one end 38 of the belt conveyor for passage to the table.

In accordance with the above described construction, a longitudinal opening or space 40 is left between the edge portions 21 and 28 of the members 13 and 26, and between the edge portions 22 and 29 of the members 14 and 27, and we provide for the movement of a line or train of cans under these open portions with the open top of the can registering with the longitudinal openings in the table, so that operators positioned at opposite sides of the table may move material to be canned from the concave members 13 and 14 laterally across the table and into the cans. This can feeding mechanism is identical on opposite sides of the table and hence a description of the mechanism at one side will suffice for both. The can feeding mechanism here comprises a pair of elongated horizontal endless conveyors 42 and 43 which extend longitudinally under the table for substantially the full length thereof and which are positioned in vertical alignment, as seen in Figures 3 and 4, and contained between the upright member 12b and an adjacent inner upright member 12c. The conveyor 42 consists of an endless chain which is supported at opposite ends of the table on sprockets 44 and 46 and is carried along its upper flight 47 on a guide means 48. This means, as illustrated in Fig. 4, consists of a pair of angle bars 49 and 51 between which is mounted a center bar 52 which is supported between the members 49 and 51 by spacers 53 and 54. The upper flight 47 of the chain rides directly on the center bar 52 between the angle members 49 and 51. Mounted across the top of the angle members are a pair of elongated plates 56 and 57 which provide a platform or rest for the bottoms 58 of cans 59 fed by the mechanism. The chain 42 is preferably of a common link type and secured to certain of the links are a plurality of longitudinally spaced can engaging elements 61. These elements are in the form of lugs and project upwardly from the top flight 47 of the chain and extend through a space 62 defined between the plates 56 and 57 to engage the base portions of the cans to carry the same longitudinally over the plates 56 and 57. A pair of side rails 63 and 64 are supported on the angle members 49 and 51 in elevated position thereover for guiding the can longitudinally along the guiding means. The lower flight 68 of the conveyor is supported on a roller 78 carried by an intermediate upright frame member 77.

The other conveyor 43, as aforementioned, is also mounted between the upright supporting members 12b and 12c and is arranged with the top and bottom flights 66 and 67 respectively above and below the top flight 47 and the bottom flight 68 of the conveyor 42. The conveyor 43 comprises a pair of endless chains, preferably of standard link construction, and which are carried by pairs of sprocket wheels 69, 71, 72 and 73 at opposite ends of the table. The upper flights 66 of the two chains are carried in hori-

zontal guide means 75 including a longitudinal angle bar 74 at the top of the upright member 12c and the angle bar 32 aforementioned at the top of the upright member 12b. The lower flights 67 of the conveyor are supported by a pair of rollers 76 intermediate the length of the table and which are supported from the intermediate upright frame member 77.

As an important feature of the can feeding mechanism, the conveyor 43 is formed with a plurality of substantially continuous plates 78 which are carried by the two chains forming the conveyor. The opposite side edge portions 81 and 82 (see Figure 4) of the plates are secured to lugs 83 and 84 carried by the two chains, whereby the plates are positioned horizontally across the opening 40. Preferably, the plate is of somewhat greater horizontal width than the opening 40 so as to underlie the table top portions 22 and 29 and preferably also, the guide means for the upper flight of the conveyor is so related to these table top portions as to cause the plates to lie directly under and in close proximity to the edge portions of the opening 40.

Each of the plates 78 is provided with a central opening 88 therein (see Figures 5 and 6) which is adapted for registration with the open can top. To facilitate this registration and also to substantially seal the plate at the top of the can, the plate is provided with a depending circular flange 87 surrounding the opening 88 which is adapted to fit directly into the interior of the can, so as to positively hold the opening 88 and can in alignment and the plate in proper seated position on the can.

In order to properly engage the plates with the cans, the two conveyors are driven in synchronism so that the upper flights of the two conveyors will move in the same direction at an identical speed, whereby the cans and two conveyor flights will move together as a unit. This unitary movement of the cans and conveyor flights is provided for over substantially the full length of the material table and as here shown, between upright frame members 12d and 12e, between which the guide means 48 and 75 for the upper conveyor flights are preferably horizontal and parallel. In this manner, as the conveyor flights approach the parallel part of the guide means, that is an end 88 of the guide means adjacent the upright member 12e, the upper conveyor flight 66 preferably descends towards the end 88 while the lower conveyor flight 47 inclines upwardly as it approaches such end. In this manner the cans are elevated as they pass to the end 88 while the plates are simultaneously lowered and the timing is such that the flanges 87 on the plates drop into the open tops of the cans as the cans and conveyors pass to the end 88 of the guide means. Throughout the full length of the parallel part of the guide means the plates are held firmly upon the tops of the cans. At the opposite end 88 of the parallel part of the guide means the upper conveyor flight 66 and the can supporting guide means 48 diverge from each other as seen in Figure 8 of the drawings, so as to simultaneously lower the cans and raise the plates, whereby the plate flanges 87 will be lifted clear of the top of the can and away from any fruit or material protruding from the top of the can. This is particularly important where the machine is used for packing peach halves, for in such case the cans are filled so that ordinarily a peach half will protrude from

the top of the can. In such case, if the cans 59 and the plates 78 are not simultaneously separated from each other, the flanges will engage and cut or break the surface of the protruding fruit. As will be seen from Figures 2 and 8, the upper guide means 75 is inclined upwardly from the end 89 while the lower guide means 48 extends downwardly from such end. The roller 91 is provided at the end 88 of the guide means 75 for depressing the upper chain flights to the parallel part of the guide means.

Any suitable means may be used for feeding cans to the conveyor flight 41, such as the screw means 92 here shown adjacent the end sprocket 46 of the conveyor. Similarly, any suitable means may be used for removing the filled cans from the opposite end of the conveyor. As here shown a discharge chute 93 is provided at the last named end which extends longitudinally, laterally and downwardly from the guide means 48 adjacent the end 89. The cans pass from the guide means 48 onto the adjacent end of the discharge chute and thence pass laterally and downwardly and longitudinally to a discharge conveyor belt 94. During such movement the cans are supported between a pair of guide rails 96 and 97.

Preferably, all of the several moving parts of the machine are connected to a single drive means, such as an electric motor 98, here shown for providing a unitary and synchronous drive for the several parts. The motor is here connected by way of a variable speed pulley 99 and belt 101 to a master drive wheel 102 carried on a cross-shaft 103. Sprocket wheels 104 carried by this shaft are connected by chains 106 to sprocket wheels 107 mounted on a second cross-shaft 108. Sprocket wheels 109 on the last mentioned shaft are connected by chains 111 to sprocket wheels 112 mounted on a cross-shaft 113 which carries the drive sprockets 44 of the conveyor 42. Sprocket wheels 114 mounted on this shaft are connected by chains 116 to a cross-shaft 117 which carries and drives the sprocket wheels 71, the latter being operatively connected to sprocket 44 by a chain for driving the conveyor 42.

We claim:

1. In a can supporting and feeding mechanism adapted for movement of a train of cans past a filling station for filling with material to be canned, an elongated horizontal endless conveyor having vertically spaced upper and lower drive and return sides, can engaging elements carried by said conveyor and projecting upwardly from the upper drive side thereof for engaging the base portions of cans mounted on said side, a second elongated horizontal endless conveyor having vertically spaced upper and lower drive and return sides arranged respectively above and below the drive and return sides of said first conveyor, the upper drive side of said second conveyor being substantially parallel to the drive side of said first conveyor and being spaced therefrom by substantially the height of cans to be supported and moved by the mechanism, a plurality of plates carried by said second conveyor and each adapted to engage the open top of a can and being formed with an opening therein for registration with the interior of the can, and means for driving said conveyors in synchronization.

2. In a can supporting and feeding mechanism adapted for movement of a train of cans past a filling station for filling of said cans with material to be canned, an elongated horizontal

endless conveyor having vertically spaced upper and lower drive and return sides, can engaging elements carried by said conveyor and projecting upwardly from the upper side thereof for engaging the base portions of cans mounted on said side, a second elongated horizontal endless conveyor having vertically spaced upper and lower drive and return sides arranged respectively above and below the drive and return sides of said first conveyor, means for supporting said drive sides in parallel relation for the greater part of their length between a pair of longitudinally spaced ends and spaced vertically for receipt of a can in upright position therebetween, means for driving said conveyors at the same speed and said drive sides in the same direction, means for guiding the upper of said drive sides downwardly to one of said ends and upwardly away from the other of said ends in the direction of movement of said side, means for guiding the lower of said drive sides upwardly to said first end in the direction of travel of said side, can engaging elements carried by said first conveyor and projecting upwardly from the lower of said drive sides for engagement with the base of said cans, and a plurality of plates carried by said second conveyor and each adapted to engage the top of a can and being provided with an opening therein for registration with the interior of the can.

3. A can conveying and filling machine comprising, an elongated trough for material to be canned, an elongated horizontal endless conveyor parallel to a longitudinal edge of said trough and positioned with the upper and lower flights thereof below said last mentioned trough edge, can engaging elements carried by said conveyor and extending upwardly from the upper flight thereof for engagement with the base of cans rested thereon, another elongated endless conveyor positioned in substantially vertical alignment to said first conveyor and arranged with the upper and lower flights thereof respectively above and below the upper and lower flights of said first conveyor, the upper flight of said second conveyor being substantially contiguous with said trough edge, and plates carried by said second conveyor and formed with openings adapted to register with the open tops of cans carried by the top flight of said first conveyor to facilitate movement of material from said trough across said plates and into said cans.

4. A can conveying and filling machine comprising, an elongated trough, material supporting means movable along one longitudinal edge of said trough, means directing material from said last means into said trough, an elongated horizontal endless conveyor adjacent and substantially parallel to the opposite longitudinal edge of said trough and positioned with the upper and lower flights thereof below said last mentioned trough edge, can engaging elements carried by said conveyor and extending upwardly from the upper flight thereof for engagement with the base of cans rested theron, another elongated endless conveyor positioned in substantially vertical alignment to said first conveyor and arranged with the upper and lower flights thereof respectively above and below the upper and lower flights of said first conveyor, the upper flight of said second conveyor being substantially contiguous with said second named trough edge, and plates carried by said second conveyor and formed with openings adapted to register with the open tops of cans carried by the top flight of

said first conveyor to facilitate movement of material from said trough across said plates and into said cans.

5. A can supporting and feeding mechanism adapted for movement of a train of cans past a filling station, comprising, a pair of horizontally disposed endless conveyors having vertically opposed sides movable horizontally in a common direction and adapted to receive a can in upright position therebetween, means for driving said conveyors at the same speed, can engaging elements projecting upwardly from the lower of said sides for engagement with said cans, a plurality of plates carried by the upper of said sides each adapted to directly engage the top of a can and being provided with an opening therein for registration with the interior of the can, means for supporting said sides in parallel relation for the greater part of their length between a pair of longitudinally spaced ends, means for guiding said upper side downwardly to one of said ends and upwardly and away from the other of said ends in the direction of movement of said side, means for guiding the lower of said sides upwardly to said first end in the direction of travel of said side, means for feeding cans onto the lower of said sides at a portion thereof in advance of said first end whereby the can will be raised to said first end while said plates are being lowered to said end, a can discharge chute extending laterally and downwardly from the second end of said lower side whereby the parting of each can from its engaged plate will be effected by a lowering of the can and a raising of the plate so as to clear the sides of the plate opening from material projecting from the top of the can, and a conveyor at the discharge end of said chute for removing said cans.

6. A can supporting and feeding mechanism adapted for movement of a train of cans past a filling station, comprising, a pair of horizontally disposed endless conveyors having vertically opposed sides movable horizontally in a common direction and adapted to receive a can in upright position therebetween, means for driving said conveyors at the same speed, can engaging elements projecting upwardly from the lower of said sides for engagement with said cans, a plurality of plates carried by the upper of said sides each adapted to directly engage the top of a can and being provided with an opening therein for registration with the interior of the can, means for supporting said sides in parallel relation for the greater part of their length between a pair of longitudinally spaced can entering and can discharging ends, means for guiding said upper conveyor side downwardly to said can entering end in the direction of movement of said side, means for guiding the lower of said conveyor sides upwardly to said can entering end in the direction

10 of movement of said side whereby said conveyor sides converge over a common portion of their longitudinal length approaching said can entering end and said can will be raised by said lower side in approaching said end while said plates are simultaneously lowered while approaching said end, means for guiding said upper conveyor side upwardly away from said can discharging end in the direction of movement of said conveyor side, and means for guiding said lower conveyor side downwardly and away from said can discharging end in the direction of movement of said conveyor side whereby said conveyor sides diverge away from said can discharging end over a common longitudinal portion of their length wherein the parting of each can from its engaged plate will be effected by a lowering of the can and a raising of the plate so as to clear the sides of the plate opening from material projecting from the top of the can.

20 7. A can supporting and feeding mechanism adapted for movement of a train of cans past a filling station, comprising, a pair of horizontally disposed endless conveyors having vertically opposed sides movable horizontally in a common direction and adapted to receive a can in upright position therebetween, means for driving said conveyors at the same speed, can engaging elements projecting upwardly from the lower of said sides for engagement with said cans, a plurality of plates carried by the upper of said sides each adapted to directly engage the top of a can and being provided with an opening therein for registration with the interior of the can and formed with a depending flange surrounding the opening adapted to fit into the interior of the can, means for supporting said sides in parallel relation for the greater part of their length between a pair of longitudinally spaced can entering and can discharging ends, supporting and guiding means for said conveyor sides in advance of said can entering end providing the converging of said sides to said end over a common portion of the length of said sides whereby cans will be raised to said end while said plates are simultaneously being lowered to said end for engagement and centering of said plates on said cans as the same move to said end, and support and guide means for said conveyor sides beyond said can discharging end causing said sides to diverge from said end over a common longitudinal portion of the length of said sides whereby the parting of each can from its engaged plate will be effected by a simultaneous lowering of the can and a raising of the plate so as to clear said flange from said can interior without interference with material projecting from the top of the can.
